UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE-BLADE FASTENING.

Application filed April 18, 1922. Serial No. 554,890.

To all whom it may concern:

Be it known that I, ALEXANDER T. KASLEY, a citizen of the United States, and a resident of Essington, in the county of Delaware and State of Pennsylvania, have invented a new and useful Improvement in Turbine-Blade Fastenings, of which the following is a specification.

My invention relates to turbine blading, and more particularly to fastening means therefor, and it has for its object to provide apparatus of the character designated which shall be simple in construction, which shall be capable of ready insertion and removal, and which shall insure a tight joint between a blade root and a turbine rotor.

Apparatus embodying the features of my invention is illustrated on the accompanying drawings, forming a part of this application, in which: Fig. 1 is a sectional detail view showing a turbine blade with my improved fastening means applied thereto; Fig. 2 is a sectional view taken along the line II—II of Fig. 1, and Figs. 3 and 4 are detail views showing different forms of fastening wedge elements, Fig. 3 showing a convenient means for removing wedges.

In my application, Serial #486,517, filed July 19, 1921, assigned to the Westinghouse Electric & Manufacturing Company, there is disclosed and claimed blading of the wide exhaust type adapted to receive steam laterally and to discharge it peripherally or at the tips. Owing to the extreme width of blading of this type, it is necessary to provide longitudinal slots in the rotor to receive the blade roots. In my application, Serial No. 527,674, filed January 7, 1922, also assigned to the Westinghouse Electric & Manufacturing Company, I disclose and claim a dove-tail type of connection between the roots of the blading of the type referred to and the rotor; and, in order to secure a tight fit between the elements of each joint, key means are provided to be driven in between the bottom of the root portion of each blade and the bottom of the root-receiving slot.

My present invention relates to an improved form of wedge or key mechanism to be interposed between the root of each blade and the bottom of its corresponding slot in order to insure that the dovetail surfaces on the sides of the root and at the sides of the slot shall be maintained in contact. The

wedging or keying means for each blade comprises a plurality of upper and lower wedge elements contacting alternately and in series, and adapted to be forced in position between the bottom of a slot and the bottom surface of a blade root in order to maintain the inclined surfaces of a root and a slot firmly in contact.

Referring now to the drawings for a more detailed description of my invention, I show a turbine blade 10 of the wide type having a dovetail root portion 11 adapted to fit in a dovetail slot 12 provided in the turbine rotor 13. A countersunk slot or groove 14 is provided at the bottom of the dovetail slot 12 to receive the wedging means which serve to force the inclined surfaces of the dovetail root portion 11 tightly into contact with the inclined surfaces of the dovetail slot 12.

The wedging means for holding the dove-tail connection tight preferably comprises a series of upper and lower wedge elements 16 and 17, respectively, which contact alternately with the bottom of the root portion 11 and with the bottom of the slot 14. The wedge blocks 16 and 17 are preferably similar and interchangeable. The wedge elements 16 and 17 have cooperating inclined surfaces 18 and 19, respectively. After a blade 10 is inserted in a slot, a bottom wedge 17 is then placed at the back end of the slot and a top wedge 16 is then inserted between the bottom wedge and the bottom of the root portion 11 and is then driven in position, the cooperating inclined surfaces 18 and 19 insuring that the upper surface of the wedge block 16 shall cooperate with the root portion 11 in order to secure a tight fit of the dovetail connection. Thereafter, succeeding blocks 17 and 16 are inserted in the same manner, each block 16 being driven tightly in place in the manner and for the purpose stated. After all of the blocks are inserted, a suitable end plate member 20 is secured in position with respect to the rotor 13 by any suitable means, the end plate member being adapted to contact with the last wedge 16 of each series in order to hold said wedges in position.

Any suitable means may be used in order to insure that each of the last wedge blocks 16 shall contact with the plate 20, for example, I show set screws 21 which are adapted to be adjusted for this purpose.

The last block 16 may also be maintained in position merely by properly adjusting the tap screws 23 shown for holding the plate 20 on the rotor 13. If the latter mode of holding the last blocks is resorted to, then such blocks may be ground or shims may be provided in order to insure firm contact between the blocks and the blade.

In order to assure ready removal of the blocks 16 and 17 when it is desired to remove a blade, the top series of blocks 16 may be provided with threaded openings 25 to receive the screw-threaded end 26 of a tool 27, which may be inserted in the slot 14 for the purpose of pulling out each of the top wedge blocks 16. In Figure 4, I show a modified form of wedge block 16 provided with a T-head portion 28 which may be engaged by a hook, pinchers, or the like, for removal.

From the foregoing, it will be apparent that I have devised wedging mechanism for use in connection with a dovetail joint which shall insure that the members of such joint shall at all times be maintained firmly in contact, the wedging mechanism being particularly useful for maintaining the dovetail root portion of wide turbine blades firmly in contact with correspondingly formed slots in a rotor.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. The combination with a turbine rotor, having a plurality of longitudinal slots with outwardly converging sides and blades having complementally formed root portions fitting the slots, of a plurality of wedge blocks contacting in series and alternately with the bottoms of each slot and its corresponding blade root portion and means carried by the blocks having their thick ends disposed toward the outer end of the rotor slot, whereby the blocks may be readily removed.

2. The combination with a turbine rotor having a plurality of longitudinal slots with outwardly converging sides and blades having complementally formed root portions fitting the slots, of a plurality of wedge

blocks contacting in series and alternately with the bottoms of each slot and its corresponding blade root portion and connecting means carried by the blocks having their thick ends disposed toward the outer end of the rotor slot adapted to connect with a suitable retracting tool when it is desired to remove the wedge blocks.

3. In a turbine, the combination of a rotor having a plurality of longitudinal slots with outwardly converging sides, each of said slots being closed at one end and open at the opposite end for the insertion of blades therein, a plurality of blades having complementally formed root portions fitting into said slots, a plurality of wedge blocks contacting in series and alternately with the bottoms of each slot and its corresponding blade root portion, and means coacting with the blades and the rotor for preventing lateral movement of the blades in the slots.

4. In a turbine, the combination of a rotor having a plurality of longitudinal slots with outwardly converging sides, each of said slots being closed at one end and open at the opposite end for the insertion of blades therein, a plurality of blades having complementally formed root portions fitting into said slots, a plurality of wedge blocks contacting in series and alternately with the bottoms of each slot and its corresponding blade root portion, and an end plate secured to the rotor and bearing against the sides of the blades for preventing lateral movements of the blades in the slots.

5. In a turbine, the combination of a rotor having a plurality of longitudinal slots with outwardly converging sides, each of said slots being closed at one end and open at the opposite end for the insertion of blades therein, a plurality of blades having complementally formed root portions fitting into said slots, a plurality of wedge blocks contacting in series and alternately with the bottoms of each slot and its corresponding blade root portion, an end plate secured to the rotor and bearing against the sides of the blades for preventing lateral movements of the blades in the slots, and means associated with the end plates for holding said wedge blocks in place.

In testimony whereof I have hereunto subscribed my name this 17th day of April 1922.

ALEXANDER T. KASLEY.
